Thomas Loverde, San Antonio, Tex.

Application January 3, 1945, Serial No. 117,239

Term of patent 7 years

(Cl. D91—1)

To all whom it may concern:

Be it known that I, Thomas Loverde, a citizen of the United States, residing at San Antonio, in the county of Bexar and State of Texas, have invented a new, original, and ornamental Design for a Rotary Lawn Sprinkler, of which the following is a specification, reference being had therein to the accompanying drawing forming a part thereof, in which

Figure 1 is a view in side elevation of a rotary lawn sprinkler, showing my new unitary design.

Figure 2 is a top plan view thereof.

I claim:

The ornamental design for a rotary lawn sprinkler, as shown.

THOMAS LOVERDE.
